UNITED STATES PATENT OFFICE.

VOLNEY W. BEESON AND WALTER B. BONINE, OF PERRY, IOWA.

STEAM-ENGINE.

SPECIFICATION forming part of Letters Patent No. 402,889, dated May 7, 1889.

Application filed December 8, 1888. Serial No. 293,003. (No model.)

To all whom it may concern:

Be it known that we, VOLNEY W. BEESON and WALTER B. BONINE, citizens of the United States of America, residing at Perry, in the 5 county of Dallas and State of Iowa, have invented certain new and useful Improvements in Steam-Engines; and we do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 Our invention relates to improvements in steam-engines; and it consists in a novel construction and arrangement or combination of mechanical devices, more fully hereinafter described and claimed.

20 The essential features of the improvement consist of a headless cylinder with a centrally-situated unattached automatically-operating valve and two pistons connected to piston-rods which are of themselves suitably attached.

25 The object of the invention is to simplify the construction and operation of the parts of an engine of this class, and to render them convenient and accessible and strong and durable. 30 We attain this object by the preferred forms of construction illustrated in the accompanying drawings, wherein like letters of reference designate similar parts in the several views, and in which—

35 Figure 1 is a sectional elevation of one form of our improved engine. Fig. 2 is a top plan view of the form of valve shown in Fig. 1. Fig. 3 is a sectional elevation of a slightly-varied form of the engine. Fig. 4 is a detail 40 perspective view of the form of valve used in the engine shown in Fig. 3.

A indicates the headless cylinder, composed of two parts centrally connected by a centrally-bulged union or collar, B. In Fig. 1 the 45 exhaust-ports *a* are formed in the cylinder adjacent to the outer ends thereof, and in Fig. 2 said ports are formed nearer the center. A space, *a'*, is provided between the two centrally-situated opposing ends of the sections of the cylinder A, between and against 50 which the flange *C'* of a valve, C, is loosely seated and has alternate bearing. As shown

in Figs. 1 and 2, the said valve C is constructed of a solid disk of metal having a flange, *C'*, operating as above set forth, and 55 having a series of grooves or notches, *c*, in the upper and lower edges thereof. The union or collar B has an ingress port or connection, *b*, adapted to be connected to a boiler.

Pistons P are provided, and are of any 60 suitable or preferred construction. The said pistons are attached to piston-rods P', which in turn are connected to the ends of a yoke, P², having a central apertured enlargement adapted to slide on a rod, P³. The said piston-rods P' may be otherwise attached and connected to other mechanism, and may extend through the valve C, and be thereby continuous. We do not limit ourselves to any 65 single form of construction in this instance. 70

The valve represented in Figs. 3 and 4 is slightly modified in construction. In this instance the flange *C'* is used, as hereinbefore described. Extending from each head of the valve-disk C are solid heads *c³*, having right- 75 angular flanges *c⁴*, holding an annular disk, *c'*. The flanges or wings *c⁴*, with the outer disk, *c'*, form steam-passages. In Fig. 1 the pistons P alternately bear directly against the valve-disk C over the grooves or notches therein, 80 and in Fig. 3 the said pistons bear on the upper ends of the heads *c³* and cover the openings or passages between the same and the annular disk *c'*.

In Fig. 1 the pistons are shown as finishing 85 the upstroke, and the valve-disk C is drawn up with its flange bearing upon and closing the upper section of cylinder A. The reverse position is represented in Fig. 3. As shown in Fig. 1, the steam is exhausting from 90 the upper cylindrical section, and has commenced to flow against the lower piston, P, and will force it down, as in Fig. 3. When said lower piston, Fig. 1, reaches the extremity of the downstroke and has passed the 95 lower port, *a*, the steam exhausts and the valve-disk C drops down and its flange bears against the end of the lower cylindrical section. It will be understood that the upper piston has been drawn down, and again ready to be 100 acted upon. The steam passes through the grooves or notches *c* in this instance, and strikes against the end of the piston.

In the form shown in Fig. 3 the steam passes

through the passages formed between the heads c^3 and disks c' of the valve, and impinges or strikes full upon the end of the piston. The disk c' closes the ports a until the 5 pistons have reached the extremity of stroke, when said disks are drawn over said ports to leave them open and in condition for exhaust, as shown in the lower cylindrical section of Fig. 3.

- o The operation is substantially the same in both of the devices shown. It will be understood that we do not limit ourselves to any exact arrangement of the cylinder A, as it can be in either a vertical or horizontal position.
- 5 The main advantage gained by our improved construction is, dispensing with the use of cylinder-heads, eccentric-rod stuffing-boxes, and various minor appurtenances now commonly employed. The steam is taken the
- o opposite way from the ordinary direction, and work can be done by either end of the engine. The cylinder can be cast on a bed or used separate, as shown.

Having thus described our invention, we 5 claim—

1. The combination, substantially as de-

scribed, of the two-part cylinder provided with exit-ports and centrally with a constantly-open ingress-port, two pistons connected to move together, and the centrally-flanged valve 30 loosely seated between the pistons and provided with extended ends which project into the path of the advancing piston.

2. The combination, substantially as described, of the sectional cylinder having exit- 35 ports and connected centrally by a bulged union having a constantly-open ingress-port, a loose disk-valve having an annular flange seated loosely between the inner ends of the cylinder-sections, and provided with 40 extended ends adapted to project into the path of an advancing piston, the pistons mounted in each section of the cylinder, the piston-rods, and the yoke to connect the pistons. 45

In testimony whereof we affix our signatures in presence of two witnesses.

VOLNEY W. BEESON.
WALTER B. BONINE.
